UNITED STATES PATENT OFFICE.

THOMAS CHRISTIAN THOMSEN, OF PURLEY, ENGLAND.

FORCE-FEED LUBRICATOR.

1,233,935.

Specification of Letters Patent. Patented July 17, 1917.

Application filed September 20, 1916. Serial No. 121,198.

To all whom it may concern:

Be it known that I, THOMAS CHRISTIAN THOMSEN, a subject of the King of Denmark, residing at Purley, Surrey, England, 5 have invented certain new and useful Improvements in Force-Feed Lubricators, of which the following is a specification.

This invention relates to lubricators of the type in which the oil drawn from a reservoir 10 by a primary pump is delivered through a sight-feed or other passage to a secondary pump by which it is forced to the part required to be lubricated.

Attempts have been made to render the 15 rate of feed or supply of oil from the primary pump to the secondary pump independent of variations in the viscosity of the lubricant due to changes of temperature. For instance it has been proposed hitherto to 20 arrange a primary pump to deliver into an air vessel having a by-pass below the oil level controlled by a set screw, and to allow the oil from the air vessel to pass a needle valve to a sight feed glass and thence to the 25 secondary pump. The intention of such proposal was to obtain a constant head under which the oil could flow to the sight feed. It was thought that with increased viscosity of the oil a rise in pressure would 30 occur in the air vessel which would compensate therefor and maintain a constant feed. The coarseness of the adjustment afforded by the set screw and needle valve obviously prevented anything but very low heads or 35 pressures being possible as the slightest adjustment would cause such a rapid change in the opening as to cause a rapid drop in pressure. The above arrangement failed in practice particularly with heavy engine oils.

40 The present invention refers more particularly to lubricators capable of dealing with heavy engine oils and with which only very small quantities are pumped at each operation.

45 With such a lubricator a fine adjustment is necessary to enable accurate regulation of the quantity of oil to be fed and moreover it is desirable that means shall be provided to insure a practically constant delivery for 50 each adjustment irrespective of variations in viscosity of the oil due to changes in temperature.

According to the invention the primary pump, which may be fitted with a suction 55 valve and a delivery sealing valve of usual form, is provided with a by-pass, by which

some oil can escape back to the reservoir, and the delivery passage has an outlet, beyond the delivery or sealing valve, which is adapted to be regulated, the by-pass and outlet from the delivery passage being such as to present comparatively long frictional surfaces so as to allow for a long range of adjustment and a high average pressure. There being no air cushion in the delivery 60 passage, and the by-pass and delivery outlet being such as to present considerable resistance to the flow of oil affording a long range of adjustment, the above conditions 65 are possible.

During each delivery stroke of the pump some of the lubricant passes back through the by-pass and some through the regulated outlet of the delivery passage. By regulation of this outlet the ratio of the resistances 70 to the flow of lubricant through the outlet and through the by-pass can be set as required, and the rate of feed regulated. Once this ratio is set the average pressure within the pump chamber during the delivery 75 stroke automatically increases or decreases with the viscosity of the oil, so that the feed is maintained constant, irrespective of change in temperature or viscosity of the oil.

80 A further object of the invention is to enable flushing to be effected without interfering with the setting or adjustment of the normal rate of feed.

85 In the accompanying drawings:—

Figure 1 is a sectional elevation of one 90 form of single-feed lubricator according to the invention.

Fig. 2 is a front elevation, partly in section, of a multiple feed lubricator according 95 to the invention, the section being taken on the line II—II, Figs. 3 and 4.

Figs. 3 and 4 are side sectional elevations on the lines III—III, IV—IV, Fig. 2.

Fig. 5 illustrates on a larger scale the adjusting plug in detail.

Fig. 6 is an enlarged plan of a plug for carrying the suction check valve.

In applying the invention to one form of single feed lubricator as shown in Fig. 1, a 105 reservoir 1 for oil and provided with operating mechanism hereinafter referred to, is also provided at one side with two holes 2 and 3, one to permit the passage of a pump barrel 4 and the other to form part of a suction passage 5. A casting 6 forming the pump barrel 4 and a valve box 7 is secured 110

- to the outside of the reservoir 1. The pump barrel 4 is bored to suit a stepped plunger, the annular or stepped part 8 of which forms the plunger for the primary pump 5 and the forward or smaller end 9 forms the plunger for the secondary pump. The upper part of the valve box 7 is screw threaded to receive an upper extension or hollow plug 10, having an enlarged head or flange 11. Below the flange 11 is a hollow collar or casting 12 clamped by the plug to the valve box 7 and having a lateral passage 13 leading to a sight feed nozzle 14, the casting 12 acting as a clamp for the upper end 15 of a sight feed tube 74, the lower end of which rests in a circular groove 15 in the top of the pump barrel 16 of the secondary pump and which has a conical opening 17 to receive and conduct the oil to the front of 20 the plunger 9.
- The lower part of the valve box 7 contains a ball 18 or other suitable form of automatic suction valve which controls part only of the suction passage to the primary 25 pump, the remainder of the passage being left free to act as a by-pass. For instance the ball valve 18 may be carried in a cup 19 in a plug 20 screwed in the bottom of the valve box 7 and having a central hole 21, 30 controlled by the ball 18, leading through lateral holes 22 to an annular space 23 below the ball valve 18 and communicating with the suction passage 5. The annular space 23 also communicates with the space above the 35 ball 18 by means of a suitable by-pass passage 24 or passages, so that on the suction stroke of the primary pump plunger the ball 18 rises and oil is free to pass through the by-pass 24. On the delivery stroke of the 40 plunger 8 the ball 18 closes the central hole but the by-pass 24 allows some oil to pass back to the reservoir 1. The by-pass passages 24 are preferably formed by the provision of flats on the cup 19 of the plug 20 as shown in the enlarged plan of the plug in Fig. 6. Narrow and long passages are thereby formed offering long frictional 45 surfaces. A ball 25 or other form of non-loaded automatic check valve is provided at the bottom of a delivery passage 26 and above said valve 25 a secondary seating 27 is formed for a cylindrical plug 28 having one or more tapering flats 29 formed in it which 50 in conjunction with the seating will form a passage or outlet for the oil presenting long frictional surfaces. According to the setting of this plug 28 relative to its seating 27 so will the delivery passage be controlled. 55 In other words the recesses 29 form a constantly open outlet for the delivery passage 26, which outlet is adapted to be regulated, or determined by the setting or adjustment of the plug 28. The plug 28 has a stem 30 60 passing up the hollow plug 10 and through a screwed gland 31. The gland 31 acts as an abutment for a spring 32 coiled about the stem 30 tending to hold the plug 28 to its seating. The screwed gland 31 forms an adjustment for the plug 28, as a knob 35 on the stem 30 rests on the head 33 thereof. To facilitate fine adjustment the head 33 may be toothed and receive a spring catch or blade 34.
- The stem 30 may be lifted by the knob 35 to 75 remove the plug 28 almost entirely from its seating when an excess quantity of oil or flushing is required. This does not interfere with or alter the feed adjustment as immediately the knob 35 is released the spring 80 32 returns the plug 28 to the position to which it was set, the knob resting on top of the head 33. The oil from the delivery passage 26 enters the passage 13 which delivers the oil to the sight feed nozzle 14 from which 85 the oil drips into the inlet opening 17 of the secondary pump either directly or down a wire oil guide 36. The secondary pump plunger 9 forces the oil past a ball or other check valve 37 as usual, to the delivery 90 pipe 50.
- In operation, once the plug 28 has been set, the relative open areas of the outlet of the delivery passage and suction by-pass during the delivery stroke remain constant, and 95 similarly the relation of their resistances to fluid flow remains practically constant. Should the viscosity of the oil vary due to change in temperature the relation of the resistance of one to the other will be practically the same as before so that the delivery 100 will be practically constant.
- The plunger 8 is operated by mechanism within the oil tank 1. In one form this 105 comprises a cam or eccentric 41, which preferably has a loose roller 42 on it to reduce friction and is mounted on a shaft 43 driven in any of the ways commonly adopted with lubricators and well known in the art, so that no description of this driving mechanism is necessary. The plunger 8 is moved in one direction by a spring 44 and in the opposite direction by the cam 41, and ring 42 abutting against a head 40 on the 110 plunger 8.
- In applying the invention to a lubricator having a plurality of feeds it is sometimes preferred to use one primary pump common to all the feeders each of which is provided with a secondary pump. A lubricator of 115 this form is illustrated in Figs. 2 to 4 wherein the parts are indicated by similar reference numerals to the corresponding parts of the lubricator hereinbefore described with reference to Fig. 1.
- In this form the primary pump plunger has suction and delivery valves 18, 25, as in the form before referred to, and also a by-pass 24, but the delivery passage 26 passes first vertically and then horizontally in a 120 125
- 130

casting 52. The passage 26 has a number of branch passages 53 fitted with drip nozzles 14, which also form seatings 27 for plugs 28 provided with recesses 29 forming outlets and adjustable in a similar manner to the plug 28 before described with reference to Fig. 1. Each secondary pump barrel 16 is fitted with a separate plunger 9 having a head 59 engaging with a ring 60 on a cam 61 mounted on the driving shaft 43. Each cam 61 moves the respective plunger 9 in one direction and a spring 62 returns it in the opposite direction.

A recess 17 conducts the oil which drips from each corresponding nozzle 14 to the respective pump barrel 16. A single large drip chamber 54 is formed in the casting 52 and is covered in front by a glass plate 55 conveniently clamped by a frame 56 and screws 57.

In operation all the outlets 29 of the delivery passage 26 are regulated by adjusting the plugs 28 by means of the screwed glands 31. The primary pump supplies the delivery passage 26 with oil and the rate of flow from the nozzles 14 is adjusted according to the requirement of each feed. The oil drips into the secondary pumps and is delivered by them through oil delivery pipes to the points to be lubricated. Once the plugs 28 are adjusted, the ratio of the resistance to the flow of oil from the delivery passage, and the resistance to flow back through the by-pass will be fixed. So long as the adjustment remains unaltered the average pressure within the chamber 26 will automatically increase or decrease with the viscosity of the oil, so that the feeds are maintained constant irrespective of changes in temperature or viscosity of the oil.

It will be understood that beyond the delivery sealing valve 25, the delivery passage 26 is constantly open during operation, that is to say there is only frictional resistance to the flow of oil, no spring or other loaded valve being interposed between the outlet and said sealing valve.

At each delivery stroke of the primary pump plunger the oil has two opposite ways to flow, one way through the delivery passage and another through the by-pass. Both ways offer frictional resistance. These two resistances will vary with variations in viscosity of the oil, but once the ratio of the two has been set or determined, by adjustment of the outlet of the delivery passage as hereinbefore described, the ratio will remain the same with increase or decrease in pressure due to variations in viscosity of the oil and consequently the rate of feed through the delivery passage will remain constant. The adjustment of the outlet of the delivery passage will, however, enable the rate of feed to be regulated as desired. An adjustable rate of feed which will remain constant once

adjusted, irrespective of changes of temperature or viscosity is therefore obtainable.

I claim:—

1. A lubricator comprising a primary pump having a suction valve, a delivery sealing valve and a by-pass close to said pump, and a delivery passage beyond said delivery sealing valve, having an outlet, said by-pass and said outlet each being long relatively to its cross sectional area for the purpose of presenting long frictional surfaces to the passage of the oil, and means for regulating said outlet to vary the frictional resistance thereof for the purpose of fixing the ratio of the resistances to the flow of the lubricant through said delivery passage and through the aforesaid by-pass—during the delivery stroke of the pump—and thereby to insure a constant rate of feed of the lubricant for each adjustment irrespective of changes in viscosity of the lubricant due to changes in temperature, substantially as hereinbefore set forth.

2. A lubricator comprising a primary pump having a suction valve, a delivery sealing valve, a by-pass, and a delivery passage beyond said delivery sealing valve and having an outlet, means for regulating said outlet comprising a cylindrical plug having a tapering flat, a seating for said plug, and adjustable means for holding said plug in determined relation to said seating, substantially as and for the purposes hereinbefore set forth.

3. A lubricator comprising a primary pump having a suction valve, a delivery sealing valve, a by-pass, and a delivery passage beyond said delivery sealing valve and having an outlet, means for regulating said outlet comprising a plug having a tapering recess, a seating for said plug, a stem for said plug, a screwed gland for said stem and through which said stem passes, and a knob on the outer end of said stem adapted to rest on the outer end of said gland, substantially as and for the purpose hereinbefore set forth.

4. A lubricator comprising a primary pump having a suction valve, a delivery sealing valve, a by-pass, and a delivery passage beyond said delivery sealing valve and having an outlet, means for regulating said outlet comprising a cylindrical plug having a tapering flat, a seating for said plug, a spring for moving said plug toward said seating, means for enabling said plug to be moved away from said seating against the action of said spring, and adjustable means for limiting the return movement of said plug under the action of said spring, for the purpose of enabling the aforesaid outlet to be adjusted, and after adjustment to permit of a temporary increased opening thereof for flushing purposes without interfer-

4
ing with said adjustment, substantially as hereinbefore set forth.

5. A lubricator comprising a primary pump having a suction valve, a delivery sealing valve, a by-pass close to said pump, and a delivery passage beyond said delivery sealing valve, a plurality of secondary pumps, outlets from the aforesaid delivery passage for delivering oil to each of said 10 secondary pumps, said by-pass and said outlets each being long relatively to its cross sectional area for the purpose of present-

ing long frictional surfaces, and separate and adjustable means for regulating each of said outlets, substantially as and for the 15 purpose hereinbefore set forth.

In testimony whereof I have signed my name to this specification in the presence of two subscribing witnesses.

THOMAS CHRISTIAN THOMSEN.
